(57) **CLAIM**

The ornamental design for a clamshell container with storage compartment, as shown and described.

DESCRIPTION

FIG. 1 is a perspective view of a clamshell container with storage compartment showing my new design;

FIG. 2 is a top plan view thereof;

FIG. 3 is a left view thereof;

FIG. 4 is a right view thereof;

FIG. 5 is a rear elevation view thereof;

FIG. 6 is a front elevation view thereof;

FIG. 7 is a bottom plan view thereof;

FIG. 8 is a second perspective view thereof;

FIG. 9 shows perspective view of a second embodiment of my new design for a clamshell container with storage compartment;

FIG. 10 is a top plan view thereof;

FIG. 11 is a left view thereof;

FIG. 12 is a right view thereof;

FIG. 13 is a rear elevation view thereof; and,

FIG. 14 is a front elevation view thereof; the bottom view being identical to the first embodiment.

The broken line portion of the figure drawings of the clamshell container with storage compartment is included to show unclaimed subject matter only and forms no part of the claimed design.
